UNITED STATES PATENT OFFICE

ALLEN J. PATCH, OF RIPON, WISCONSIN

PISTON

Application filed June 26, 1929. Serial No. 373,886

This invention relates to a composite piston and particularly to such a piston which may be used in internal combustion engines.

It has heretofore been proposed to construct pistons for internal combustion engines in which the main body of the piston is made of some of the lighter metals such as aluminum and magnesium, or alloys of these metals. Because of their light weight and high coefficient of heat conductivity such metals or alloys have certain advantages over cast iron and other heavier metals in such pistons. However, those advantages are at least partially offset by the fact that the lighter metals are generally softer and are subject to rapid wear when working in a cast iron engine cylinder. To overcome this disadvantage to the use of light weight pistons in internal combustion engines, such pistons have been made in two parts, a main body part of aluminum or other light metal having high heat conductivity, and a surrounding skirt portion of cast iron or other wear-resisting metal which forms the bearing surface of the piston.

In composite pistons as heretofore manufactured, the skirt portion has been rigidly secured to the body portion at two or more points, and as the coefficient of expansion of both aluminum and magnesium, as well as their alloys, is considerably greater than that of cast iron and other heavy, wear-resisting metals, it has frequently happened that owing to the unequal expansion due to the changes in temperature to which pistons of internal combustion engines are subject ed, either one or the other of the parts, or the fastening means between them, has become damaged.

It is an object of my invention to provide a composite piston which will meet the requirements of a piston with respect to lightness, strength and durability, and which will also allow for the difference in the coefficient of expansion of the different metals from which the wear-resisting skirt and the thermally conductive light body portions of the pistons are constructed.

My invention further aims to provide a

means for attaching the skirt portion to the body portion of the piston which will permit such relative movement between the two portions as may be caused by circumferential expansion resulting from differences in the coefficients of expansion of the different metals, and thereby prevent radial distortion of or other detrimental effects upon the surrounding skirt portion.

It is also an object of my invention to provide means for attaching the skirt portion which will effectively hold the same in place upon the body portion when the piston is in operation, but which will permit the skirt portion to be readily removed by a mechanic should it become necessary to replace or repair any of the parts.

In accordance with my invention I provide a main piston body portion of some metal such as aluminum or magnesium, or an alloy of these metals which will insure the piston being sufficiently light in weight and having a high coefficient of heat conductivity, and removably secured to it a surrounding skirt of cast iron or other wear-resisting metal. The lower end of the body portion of the piston is reduced in diameter to receive the skirt which is secured thereto by means of horizontal ribs on the inner side of the skirt engaging a circumferential groove in the body portion. The lower wall of the circumferential groove is cut away at spaced intervals to permit the ribs of the skirt to be passed up therethrough and into the groove, after which the skirt is turned slightly to remove the ribs from alignment with the cut-outs and cause them to rest on the remaining portions of the lower wall of the groove and hold the two parts together. To prevent the skirt from being turned on the body portion whereby the ribs might again be brought into alignment with the cut-outs and the skirt portion separated from the body portion, a locking member

in the form of a steel spring is inserted upwardly through the cut-outs and caused to rest in the groove and form a stop against which the ends of the rib would strike should movement in the reverse direction take place.

The invention is further illustrated in the accompanying drawings and description, but it is to be understood that this further illustration and description is an exemplification of the invention and that the same is not limited thereto except as set forth in the appended claims.

In the drawings:

Figure 1 is a vertical sectional view taken on line 1—1 of Fig. 2 of a piston embodying my invention;

Fig. 2 is a sectional view taken on line 2—2 of Fig. 1;

Fig. 3 is an elevational view of the piston with the skirt portion removed;

Fig. 4 is a vertical sectional view of the skirt portion;

Fig. 5 is a transverse sectional view of the skirt portion taken on line 5—5 of Fig. 4, and

Fig. 6 is an enlarged sectional view taken through the fastening means between body and skirt portions of the piston.

Referring now to the drawings, the numeral 1 indicates the main body portion of the piston which is made of a light weight metal having a high coefficient of heat conductivity such as aluminum or magnesium, or an alloy of these metals. The body portion 1 has the usual bearing 2 for the wrist pins and the grooves 3 for the piston rings. Just below the lowermost groove 3 the body portion is reduced in diameter to form a portion 4 over which the skirt 5, which is of cast iron or other wear-resisting metal, is slipped. The major part of the portion 4 has an external diameter which is somewhat less than the internal diameter of the skirt 5 so that a space 6 is formed therebetween, but the lower end 7 of the portion 4 has a diameter for a short distance of the proper size to fit the inside of the skirt.

To secure the skirt portion 5 to the body portion 1, the lower end of the latter is provided with a circumferential groove 8 into which transverse ribs 9 on the inside of the skirt 5 are received. As clearly shown in Figs. 1, 3 and 4, the ribs 9 and the thickened portion 7 of the piston on which the skirt bears are approximately midway between the two ends of the skirt, and the groove 8 and the thickened portion 7 are also approximately in line with the center of the piston pin bosses 2. Also, as shown in Fig. 1, the skirt 5 does not contact with any part of the piston except in the region of the thickened portion 7.

The part 4, being reduced in diameter, insures the space 6 being maintained between the inner wall of the skirt and the outer wall of the piston, and the top of the skirt terminating short of the enlarged upper end of the piston insures an opening at

all times between its beveled upper end and the piston.

To permit access of the ribs 9 into the groove 8 the lower wall defining the latter is cut away at spaced intervals to form cut-outs 10 through which the ribs 9 pass. After the ribs 9 have been brought into alignment with the cut-outs 10, the skirt 5 is slipped onto the body portion until the ribs strike against the upper wall of the groove 8. The skirt is then turned a distance corresponding to the length of one rib which will remove all of the ribs from alignment with the cut-outs 10 and cause them to overlie the portions between the cut-outs and thereby retain the skirt on the body portion.

The thickened end 7 is provided with a recess 11 at the upper part of two of the cut-outs into which locking members 12, preferably in the form of a flat steel spring, are inserted. These locking members are wider than the ribs 9 and, as shown in Fig. 2, have their ends projecting out of the recesses 11 and lying adjacent both the ends of the respective ribs 9 and the upper portion of the walls defining the cut-outs 10 and thereby prevent the skirt portion from being turned on the body portion whereby the ribs might be brought into alignment with the cut-outs and the skirt separated from the body portion.

To insert the locking members 12 into the recesses 11 it is only necessary to bend them slightly and push them upwardly through the cut-outs 10. As soon as they get opposite the recesses they straighten out in the recesses 11 as shown in Figs. 1 and 2, where they overlie the lips 13 forming the lower wall of the recesses.

Should it be desired at any time to remove the skirt 5 to make repairs or replacements, it is only necessary to insert a tool through the cut-outs and again bend the members 12 to conform to the curvature of the cut-outs when they can be pulled out and the skirt is then turned until the ribs align with the cut-outs 10.

While the invention has been described with reference to the particular construction shown in the drawings, it is to be understood that various changes within the scope of the appended claims may be made.

What I claim is:

1. A piston comprising a body portion having a circumferential groove, a surrounding skirt having at least one internal rib in said groove and means permitting radial movement but preventing substantial rotary movement between the body portion and the skirt, said means having no positive connection with either the body portion or the skirt.

2. A piston comprising a body portion having a circumferential groove, a sur-

rounding skirt having at least one internal rib in said groove and a spring member forming an abutment for the end of the rib for preventing substantial rotary movement between the body portion and the skirt.

3. A piston comprising a body portion having a circumferential groove, a portion of the lower wall defining said groove being 10 cut away to form a cut-out, the body portion also having a recess adjacent the upper end of the cut-out, a skirt portion having an internal rib in said groove and means partially within said recess for preventing substantial movement between the skirt and body portion.

In testimony whereof I affix my signature.
ALLEN J. PATCH.
